UNITED STATES PATENT OFFICE.

JEREMIAH P. JOHNSON, OF DETROIT, MICHIGAN.

DESIGN FOR A RAIL.

SPECIFICATION forming part of Design No. 30,958, dated June 6, 1899.

Application filed May 1, 1899. Serial No. 715,247. Term of patent 14 years.

To all whom it may concern:

Be it known that I, JEREMIAH P. JOHNSON, a citizen of the United States, residing at Detroit, in the county of Wayne and State of Michigan, have invented and produced a new and original Design for a Rail, of which the following is a specification, reference being had therein to the accompanying drawings.

In the drawings, Figure 1 is a perspective view of a rail, showing my design; and Fig. 2 is a cross-section on line x x thereof.

The invention relates to a design for a rail adapted for use as a capping-rail for wooden boxes, and the leading feature of my design consists in a rail of the type referred to comprising an arch-shaped strip or cap, the ends being at an acute angle to the plane connecting the lower edges thereof with the depending lip around the apertures, as shown in Fig. 2.

The rail is arch-shaped, as shown, the end faces A being, as shown, at an acute angle to the plane B, which is a line drawn to connect the lower points thereof. The convex face has a series of separated round depressions C therein around apertures E through the rail and the under face a series of circular rings D around the apertures, as shown in the cross-section Fig. 2.

What I claim as my invention is—
The design for a rail, substantially as herein shown and described.

In testimony whereof I affix my signature in presence of two witnesses.

JEREMIAH P. JOHNSON.
